DESIGN FOR A BUCKLE

Harland F. Wright, Woodside, N. Y.

Application November 16, 1935, Serial No. 59,616

Term of patent 3½ years

To all whom it may concern:

Be it known that I, Harland F. Wright, a citizen of the United States of America, residing in Woodside, L. I., county of Queens, and State of New York, have invented a new, original, and ornamental Design for a Buckle, of which the following is a specification, reference being had to the accompanying drawing, forming part thereof.

I claim:

The ornamental design for a buckle substantially as shown.

HARLAND F. WRIGHT.
